UNITED STATES PATENT OFFICE.

WILLIAM F. REACH, OF CHICOPEE, MASSACHUSETTS.

DISCUS.

1,134,008.

Specification of Letters Patent. Patented Mar. 30, 1915.

Application filed May 26, 1914, Serial No. 841,071. Renewed February 3, 1915. Serial No. 5,975.

To all whom it may concern:

Be it known that I, WILLIAM F. REACH, a citizen of the United States, residing at Chicopee, Massachusetts, have invented certain new and useful Improvements in Disci, of which the following is a specification.

My invention is an improved metal discus, it being the object of the invention to make a construction of great simplicity, presenting a perfectly smooth exterior with the least possible resistance to the air, together with freedom from seams or joints to tear the hands.

In the accompanying drawing, Figure 1 shows my improvement in elevation, and Fig. 2 is a section through the center.

The invention includes a formed ring A, and a center post B, with two shells C, supported by the post and riveted thereto, presenting flattened faces at this point, the outer parts of the shells being tapered to contact with and be bent around the ring, as shown in the sectional view, rivets D passing through the shells to securely hold the parts together. Where the edges of the shells come together at the periphery of the ring they are soldered or brazed.

It will be seen that there is thus formed a

discus of few parts, easily put together; with the parts safely secured and presenting such a smooth surface as to offer the least possible amount of resistance as it sails through the air, with no seams or joints likely to open up and affect the hands of the user.

What I claim is:

1. A discus comprising a ring and a shell exterior bent around the ring and secured thereto, and a central support for the shell, substantially as described.

2. A discus comprising two shells, a ring within the shells and secured to the shells, and a central support, substantially as described.

3. A discus comprising two shells having their edges brought together, and a ring located within the space formed by the shells and secured thereto, substantially as described.

In testimony whereof, I affix my signature in presence of two witnesses.

WILLIAM F. REACH.

Witnesses:

EARL C. DANIELS,
HOWARD L. HOLT.
